(57) **CLAIM**

The ornamental design for vehicle service system console cabinet, as shown and described.

DESCRIPTION

FIG. 1 is a front perspective view of a vehicle service system console cabinet with side doors;

FIG. 2 is a rear perspective view of the vehicle service system console cabinet with side doors;

FIG. 3 is a front elevational view of the vehicle service system console cabinet with side doors;

FIG. 4 is a right elevational view of the vehicle service system console cabinet with side doors;

FIG. 5 is a rear elevational view of the vehicle service system console cabinet with side doors;

FIG. 6 is a left elevational view of the vehicle service system console cabinet with side doors;

FIG. 7 is a top plan view of the vehicle service system console cabinet with side doors;

FIG. 8 is a bottom plan view of the vehicle service system console cabinet with side doors;

FIG. 9 is a front perspective view of a vehicle service system console cabinet without side doors;

FIG. 10 is a rear perspective view of the vehicle service system console cabinet without side doors;

FIG. 11 is a front elevational view of the vehicle service system console cabinet without side doors;

FIG. 12 is a right elevational view of the vehicle service system console cabinet without side doors;

FIG. 13 is a rear elevational view of the vehicle service system console cabinet without side doors;

FIG. 14 is a left elevational view of the vehicle service system console cabinet without side doors;

FIG. 15 is a top plan view of the vehicle service system console cabinet without side doors; and,

FIG. 16 is a bottom plan view of the vehicle service system console cabinet without side doors.

The elements in dashed lines do not form a part of the claimed design.
